CLAIM

The ornamental design for a retractable awning and partial room combination, as shown and described.

DESCRIPTION

FIG. 1 is an upper-right perspective view illustrating my ornamental design comprising a retractable awning and partial room combination in accordance with a first embodiment;

FIG. 2 is an upper-left perspective view thereof;

FIG. 3 is a first lower-right perspective view thereof;

FIG. 4 is a second lower-right perspective view thereof;

FIG. 5 is a rear elevation view thereof;

FIG. 6 is a front elevation view thereof;

FIG. 7 is a top plan view thereof;

FIG. 8 is a bottom plan view thereof;

FIG. 9 is a right-side elevation view thereof; and

FIG. 10 is a left-side elevation view thereof.

FIG. 11 is an upper-right perspective view illustrating my ornamental design comprising a retractable awning and partial room combination in accordance with a second embodiment;

FIG. 12 is an upper-left perspective view thereof;

FIG. 13 is a lower-left perspective view thereof;

FIG. 14 is a lower-right perspective view thereof;

FIG. 15 is a front elevation view thereof;

FIG. 16 is a rear elevation view thereof;

FIG. 17 is a top plan view thereof;

FIG. 18 is a bottom plan view thereof;

FIG. 19 is a right-side elevation view thereof; and

FIG. 20 is a left-side elevation view thereof.

FIG. 21 is an upper-right perspective view illustrating my ornamental design comprising a retractable awning and partial room combination in accordance with a third embodiment;

FIG. 22 is an upper-left perspective view thereof;

FIG. 23 is a lower-right perspective view thereof;

FIG. 24 is a lower-left perspective view thereof;

(Continued)

FIG. 25 is a rear elevation view thereof;
 FIG. 26 is a front elevation view thereof;
 FIG. 27 is a top plan view thereof;
 FIG. 28 is a bottom plan view thereof;
 FIG. 29 is a right-side elevation view thereof; and
 FIG. 30 is a left-side elevation view thereof.
 FIG. 31 is an upper-right perspective view illustrating my
 ornamental design comprising a retractable awning and
 partial room combination in accordance with a third embodiment;
 FIG. 32 is an upper-left perspective view thereof;
 FIG. 33 is a first lower-left perspective view thereof;
 FIG. 34 is a second lower-left perspective view thereof;
 FIG. 35 is a front elevation view thereof;
 FIG. 36 is a rear elevation view thereof;
 FIG. 37 is a top plan view thereof;
 FIG. 38 is a bottom plan view thereof;
 FIG. 39 is a right-side elevation view thereof; and,
 FIG. 40 is a left-side elevation view thereof.
 In the drawings, the broken lines depict environmental
 subject matter only and form no part of the claimed design.
